UNITED STATES PATENT OFFICE

ROBERT P. GREENLEAF, OF HUDSON, OHIO, ASSIGNOR TO FRANK BILLINGS, OF
CLEVELAND, OHIO.

DIGGING AND CONVEYING APPARATUS.

1,189,443.

Specification of Letters Patent.

Patented July 4, 1916.

Application filed June 9, 1911. Serial No. 632,106.

To all whom it may concern:

Be it known that I, ROBERT P. GREENLEAF, a citizen of the United States, residing at Hudson, in the county of Summit and State of Ohio, have invented a certain new and useful Improvement in Digging and Conveying Apparatus, of which the following is a full, clear, and exact description.

This invention relates to digging and conveying apparatus adapted especially for use in mines to convey ore and other loose material at the inner end or working face of the drift rearwardly to a point where it may be dumped or discharged into a car which may be run into the mine up to the rear end of the machine.

The object of the invention is to provide loading machinery which is especially adapted for use in a rather narrow drift or tunnel of a mine, and by means of which material can be picked up and conveyed rearwardly through the machine to dumping position in a very satisfactory and economical manner.

25 A machine constructed in accordance with my invention preferably includes a suitable frame which may be supported on trucks, the wheels of which engage the rails of the track laid along the bottom or floor of the tunnel. This frame is provided with a rather long boom which is pivoted to the frame at the rear end thereof, so as to swing horizontally and projects forwardly beyond the forward end of the frame. The boom 30 supports a track along which is adapted to be run a trolley to which a digging and conveying bucket is attached. The bucket is 35 constructed and operated in a manner such that it is filled by drawing the same forwardly along the forward end of the track through the loose material, and it is then 40 adapted to be conveyed rearwardly to dumping position. As before stated, the boom is pivoted to swing horizontally, and the range 45 of movement is such that the bucket may collect the material at any point between the side walls of the tunnel. Furthermore, the track is provided at its forward end with a movable section which is arranged 50 to be raised or lowered so that the bucket may be filled with material, regardless of its height above the tunnel floor.

The invention also resides in the particular construction of the bucket and of the trolley which supports the same, and in the

means for causing the bucket to be filled during its forward movement, and after being filled to be tilted so as to prevent loss of any material while the bucket is being conveyed to dumping position.

Other novel features consist in the specific means which I have provided for automatically opening the rear door of the bucket and for simultaneously tilting the bucket so that the contents may be discharged from the latter when in dumping position. 65

The above and other novel features constitute my invention, which may be further briefly summarized as consisting in certain novel details of construction and combinations and arrangement of parts which shall be described in the specification and set forth in the appended claims. 70

In the accompanying sheets of drawings, Figure 1 is a top plan view of the loading machine constructed in accordance with the preferred form of my invention; Fig. 2 is a side view of the same; Fig. 3 is a side view of the forward end of the machine; Fig. 4 is a side view of the rear end of the machine; Fig. 5 is a diagrammatic plan view showing particularly the arrangement of the reciprocating motor, sheaves and ropes for shifting the boom back and forth; and Fig. 6 is an end view of the same looking toward the right of Fig. 5 and showing the boom in section. 75 80 85

The loading machine includes a frame 10 which is preferably supported on trucks 11, the wheels of which engage the rails of track 12 which is laid on the bottom or floor of the mine tunnel. The frame is provided with a base or floor on which are supported motive devices, hoists and other parts of the operating mechanism for the various parts of the machine. The frame is provided also at the corners with upright members 13 which are connected at the top by side frame members 14, the latter extending rearwardly a considerable distance beyond the main portion of the frame, as shown clearly in Figs. 1, 2 and 4. At the top of the frame and extending between the side members 14 are horizontal cross members 15, and beneath the front member 15 are horizontal boom supporting members 16 shown clearly in Fig. 3. The frame is preferably built almost entirely of structural members, such as angles and channels. Pivotaly supported at the rear of the rearward extension of the

frame by means of a vertical bolt 17, and extending forwardly beyond the frame between the cross member 15 and the cross member 16 is a boom 18 which is adapted 5 to be swung back and forth in a manner hereinafter described. The boom which is preferably formed of structural members supports a track 19 which is I-shaped and is formed of two channels arranged back to back and spaced a suitable distance apart. The track is arranged to swing with the boom and is in the same vertical plane therewith. At about the center of the frame, it will be seen that the track has a decided 10 inclination forward and downward, and that part of the track from the rear end of the boom to substantially the front vertical members 13 is fixed relative to the boom. The forward end 19a of the track is, however, pivoted to the relatively fixed portion 15 in a manner such that this forward section may be raised or lowered vertically with reference to the fixed portion of the track and with reference to the boom. The rear 20 end of the track is also inclined downwardly to cause the bucket to be tilted when it reaches dumping position, as will be explained.

Arranged to run along the track 19 is a 30 trolley 20 which supports a digging and conveying bucket 21. The trolley includes two side frame members 20a provided with two sets of inwardly extending studs or 35 axles 22, at the inner ends of which are two sets of wheels 23, those supported by one of the side frame members engaging the channel on one side of the track, and those supported by the other side frame member 40 engaging the channel on the opposite side of the track.

The bucket is trunnioned between the 45 sides of the trolley by means of inwardly projecting studs 24 which are connected to the opposite sides of the bucket somewhat near the center of the latter. This bucket has an open top and front, and the digging part of the bucket is at the lower front edge thereof. The sides and bottom of the bucket are closed and at the rear there is a swinging door 25 which is supported on two sets of pivoted arms 26 and 27. At the rear of the trolley and extending between the sides thereof is a shaft 28, the ends of which project beyond the sides of the trolley and are 50 provided with crank arms 29. The ends of the cranks are pivotally connected to forwardly projecting links or arms 30 which are pivoted to the sides of the bucket near the top thereof, as shown at 31. These cranks 55 and links 30 are for the purpose of holding the bucket in digging position when moved forwardly, and of tilting the bucket after it has been filled, and just before it is moved rearwardly through the machine. 60 65 By means of coil springs 32, which sur-

round the shaft 28, the cranks are turned so as to cause the cranks and links to assume a dead center position, or a position wherein they are in substantial alinement, as shown in Fig. 3. When the cranks and links 70 are in the position stated, which may be termed the locking position, they effectively hold the bucket against turning or rocking movement either in a counterclockwise direction or in a clockwise direction as the 75 structure is viewed in Fig. 3. To prevent turning of the bucket in a counterclockwise direction, the parts 29 and 30 serve as tension members, and to prevent turning of the bucket in a clockwise direction these parts 80 serve as compression members or as toggle members, they being then held on or very slightly beyond their dead center position by any suitable stop member 29a, such as shown in Fig. 3. At the middle of the shaft 85 is fixed a sheave 33 which is engaged by a tail rope 34 which extends at least partially about the sheave 33 and is dead-ended thereon, this tail rope being for the purpose of first turning the shaft 28 through approximately a half revolution, so as to tilt the bucket about 30° after it has been filled, and of substantially pulling the bucket upwardly and rearwardly along the track to dumping position.

The bucket is designed to be drawn forwardly along the track, so that it may be filled by scooping up the material, by means of one or more ropes 35, which may be termed "head ropes", which are preferably 90 attached to the front axles or wheel supporting studs 22, and thence extend forwardly about a pair of sheaves 36 mounted upon the forward end of the pivoted track section 19a. The trend of these ropes, as well as of 105 the other ropes, will be explained in detail later.

The different parts of the machine, including the boom, track and bucket are operated and controlled by mechanism located 110 upon the floor of the machine, the motive devices of this mechanism being controlled by the operator while standing on a platform 37 along the side of the lower portion of the frame. For operating the bucket and track, one or more air engines 38 are employed, these engines being shown most clearly in Fig. 1 by dotted lines. The crank shaft of these engines is geared to a counterclockwise 115 shaft 39 which in turn is geared to two drum shafts 40 and 41. The drum shaft 40 has mounted thereon two drums 42 and 43 which are adapted to be alternately clutched to the drum shaft to wind in the head ropes and unwind the tail rope, or to wind in the 120 tail rope and unwind the head ropes. The drum shaft 41 has mounted thereon, a drum 41a which receives the cable for raising or lowering the pivoted track section.

From the drum 42, the head-ropes extend 125

laterally about sheaves 44, thence upwardly about sheaves 45, thence rearwardly about sheaves 46, thence about sheaves 47, arranged at the rear end of the frame, thence 5 forwardly along and between the side members of the boom and track about suitable sheaves 48 and 49, thence about sheaves 50, (see Fig. 1) carried by the pivotal section of the track, and thence about the sheaves 10 36 at the forward end of the track and to the trolley of the bucket, as before described.

From the drum 43, the tail rope extends laterally about a sheave 51, thence upwardly about a sheave 52, thence rearwardly to 15 the rear end of the frame about sheaves 53 and 54, the latter being supported at the lower side and rear of the boom. From the sheave 54, the tail rope extends forwardly in a diagonal direction to the sheave 33 on 20 the shaft 28 of the trolley.

The rope 55 for raising and lowering the pivoted section 19^a of the track is dead-ended at 56 to one corner of the frame (see Figs. 1 and 2); thence the rope 55 extends 25 forwardly about a sheave 57 carried by the boom, thence forwardly about a sheave 58 at the outer end of the boom, thence downwardly about a sheave 59 carried by the top of the pivoted track section, (see 30 Figs. 2 and 3), thence upwardly about a sheave 60 carried by the boom, thence rearwardly about a sheave 61 also carried by the boom, thence laterally about a sheave 62 carried by the frame at one corner thereof, 35 thence rearwardly about a sheave 63, thence downwardly about a sheave 64, and thence laterally onto the drum 41^a.

The drums 42 and 43 are provided with suitable clutches (not shown), by means of 40 which either drum may be clutched to the shaft 40, while the other is allowed to turn loosely thereon. The drums are provided with means indicated at 65 for receiving brake bands so that suitable tension may be 45 maintained on the rope or ropes being paid out. In a similar manner, the drum 41^a is provided with a clutch and brake. It will be understood that the track section 19^a is lifted by the engine and that it will descend 50 by gravity, the descent being regulated by the brake.

The boom is adapted to be swung back and forth by mechanism including a reciprocating air motor 66, comprising a cylinder, 55 and plunger 67 at the forward end of which is a cross head 68. Two cables which are connected to the cross head are employed for swinging the boom in opposite directions. One of these cables 69 is attached to one side 60 of the boom and thence extends laterally to one side of the frame about a sheave 70, thence downwardly about a sheave 71, and a sheave 72, and thence extends to and is connected to the forward end of the cross 65 head. The other rope 73 passes laterally in

the opposite direction and thence extends downwardly about a sheave 74, thence inwardly about a sheave 75, thence rearwardly about a sheave 76, thence forwardly about a sheave 77, and along the plunger 67 to the 70 cross head 68. It will be seen by this arrangement that when the plunger is moved rearwardly or in the direction indicated by the arrow, the two ropes 69 and 73 will be shifted in the direction indicated by the 75 respective arrows, and the boom will be shifted toward the far side of the machine, as viewed in Figs. 1 and 2. When the plunger is moved in the opposite direction or forwardly, the boom will, of course, be 80 swung in the opposite direction to that in which it was swung by the inward movement of the plunger.

To fill the bucket, the latter is moved forwardly along the track by winding in the 85 head ropes and allowing the tail rope to pay out. The cranks 39 and arms 30 will, because of the springs 32, assume the positions shown in Figs. 2 and 3, and consequently the bucket will be held against tilting movement/in position to scoop up the material lying loosely in the tunnel. It will be understood, of course, that the tension which is ordinarily maintained on the tail rope during the forward movement of the bucket, 90 will not be sufficient to turn the shaft 28 against the action of the springs 32. When the bucket has received the proper amount of material, the drum which receives the head ropes, will be unclutched, and the drum 95 which receives the tail rope will be clutched to the shaft so as to cause the tail rope to be wound in. Before the bucket and trolley are moved rearwardly along the track, the pull on the tail rope first turns the shaft 100 28 and cranks 29 through a half revolution, so as to cause the bucket to be tilted to prevent the material dropping from the bucket, as it is being carried rearwardly. The winding in of the tail rope causes the trolley and 105 the bucket with its load of material to be conveyed rearwardly along the track. The upright members of the frame and the various other parts supported by the frame are so arranged that the bucket may pass directly through the frame along its course 110 to dumping position. A suitable apron or canopy 78 is arranged over the hoisting and operating mechanism to prevent any material dropping thereon.

When the bucket approaches the rear end of the track, the rear pair of wheels of the trolley ride down the incline so as to cause the bucket to be tilted to the position shown in dotted lines in Figs. 2 and 4. At the same 115 time that the bucket is being tilted, a hook or projection 79 on the door is engaged by a swinging stirrup 80 supported by the boom near the inclined portion of the track. As the bucket is being tilted, the rear door of 120 125 130

the bucket is thus lifted so that the contents of the bucket may be discharged into a car 81 or other member arranged to receive the material. This car as shown in Figs. 2 and 4, is run into the tunnel along the track upon which the loading machine rests.

The bucket can now be moved forwardly along the track to receive another load, the bucket passing down the track either by 10 gravity or by the pull on the head ropes. As the bucket starts from dumping position, the rear door is again closed and the bucket itself assumes the position to scoop up another load, the cranks 29 turning to 15 the dead center position shown in Figs. 2 and 3, as soon as the tension on the tail rope is removed, or becomes less than the torsional pull of the springs 32. When necessity demands, the pivoted section of the 20 track can be lowered from time to time so as to enable the bucket to remove the material layer by layer. Also as necessity demands, the boom may be swung backward and forward to collect the material at all 25 points between the side walls of the tunnel.

The movements of the various parts above described are controlled through a number of levers and brake pedals which are grouped so as to be within convenient reach of the 30 operator when standing on the platform before mentioned. These various parts are shown in rather conventional manner on Figs. 1 and 2. In these figures 82 represents the throttle lever controlling the reciprocating air motor for shifting the boom; 83 represents the engine throttle; 84 represents a 35 double throw lever for controlling the two clutches controlling the bucket winding drums; and 85 represents the lever controlling the clutch which is used to connect the track raising and lowering drum to its shaft. At 86, 87 and 88 are shown the various 40 brake pedals for controlling the movements of the different drums, especially when unwinding. The connections of the levers and brake pedals to the various parts which they control need not be illustrated other than in the simple manner here shown, for the reason that it is believed they do not directly involve any patentable novelty.

While I have described only the motive devices here shown, that is the air engines and reciprocating air motor for actuating the different parts of the machine, nevertheless it is to be understood that as far as the main features of the invention are concerned, different types of motors or motive devices may be employed which may be operated by other sources of energy than compressed air.

60 Having thus described my invention, what I claim is:

1. In a digging and conveying apparatus, a frame, a track extending lengthwise of the frame, a trolley adapted to be guided along 65 the track, a digging and conveying bucket

carried by the trolley, a head rope connected to the trolley for moving the same forwardly along the track, a tail rope for moving the trolley rearwardly along the track, and mechanism intermediate of the tail rope and the bucket for tilting the bucket when tension is placed on the tail rope to move the trolley and bucket rearwardly. 70

2. In a digging and conveying apparatus, a frame, a track extending lengthwise of the frame, a trolley adapted to be guided along said track, a digging and conveying bucket carried by the trolley, means for moving the trolley and bucket forwardly along the track, a tail rope for moving the trolley and bucket rearwardly along the track, and mechanism intermediate the tail rope and bucket for holding the bucket in digging position when it is moved forwardly by the head rope, and for tilting the bucket when tension is placed on the tail rope to move the trolley and bucket rearwardly. 75

80 3. In a digging and conveying apparatus, a frame, a track extending lengthwise of the frame, a trolley adapted to be guided along said track, a digging and conveying bucket carried by said trolley, ropes connected to the trolley for moving the same forwardly and rearwardly along the track, and means for holding the bucket in digging position 85 so as to scoop up material when moved forwardly, comprising locking members including a rotary crank carried by the trolley, and a link connecting the crank to the bucket and adapted to be swung into locking relationship with the crank. 90

95 4. In a digging and conveying apparatus, a frame, a track extending lengthwise of the frame, a trolley adapted to be guided along said track, a digging and conveying bucket trunnioned in said trolley and serving to scoop up the material when moved forwardly along the forward portion of the track, ropes connected to the trolley for moving the same forwardly and rearwardly 100 along the track, and means for tilting the bucket after it is filled comprising a crank shaft and crank carried by the trolley and a link connected to the crank and to the bucket. 105

110 5. In a digging and conveying apparatus, a frame, a track extending lengthwise thereof, a trolley adapted to be guided along said track, a digging bucket trunnioned in said trolley and adapted to scoop up the material when moved forwardly along the forward portion of the track, a rope connected to the trolley for moving the same forwardly, a crank shaft carried by the trolley, a crank secured to said crank shaft, a link pivotally 115 connecting the crank to the bucket, and a tail rope connected to the crank shaft for turning the latter so as to tilt the bucket after being filled and for drawing the bucket and trolley rearwardly along the track. 120

6. In a digging and conveying machine, a frame, a track extending lengthwise of the frame and projecting forwardly beyond the same, a trolley adapted to be guided along said track, a digging and conveying bucket trunnioned to said trolley, a rope connected to the trolley for moving the same forwardly along the track so as to cause the bucket to scoop up the material when moving along the forward portion of the track, a tail rope connected to the trolley for moving the same rearwardly along the track, and mechanism intermediate of the tail rope and the bucket for holding the bucket in the trolley during the digging period, and for tilting the bucket after it has received the material.

7. In a digging and conveying apparatus, a frame, a track extending lengthwise of the frame and projecting forwardly beyond the same, a trolley adapted to be guided along said track, a digging and conveying bucket trunnioned in said trolley, a head rope connected to said trolley for moving the same in a forward direction and for causing the bucket to scoop up material when moving along the forward portion of the track, a shaft supported by said trolley, a sheave on said shaft, a tail rope connected to said sheave, and mechanism intermediate of the shaft and bucket for holding the bucket against tilting movement during the digging period, and for tilting the bucket when said sheave is turned by the tail rope.

8. In a digging and conveying apparatus, a frame, a track extending longitudinally of the frame, a trolley adapted to be guided along said track, a digging and conveying bucket trunnioned in said trolley, a head rope connected to the trolley so as to move the same forwardly along the track, and to scoop up the material during said forward movement, a shaft supported by said trolley, cranks on said shaft, links connecting the cranks to the bucket, springs for normally holding the shaft in position such that the cranks and links prevent the tilting of the bucket during the digging action, a sheave on said shaft, and a tail rope connected to said sheave for turning the shaft so as to cause the tilting of the bucket and for drawing the trolley and bucket rearwardly along the track.

9. In a digging and conveying apparatus, a frame, a boom pivoted to said frame so as to swing horizontally, a track extending longitudinally through said frame and supported by said boom, the forward portion of the track being movable relative to the rear portion so that it may be raised and lowered, a trolley adapted to be guided along said track, a digging and conveying bucket supported by said trolley and adapted to be filled with material when moving forwardly along the movable section of the track, and ropes connected to the trolley

for moving the same back and forth along the track.

10. In a digging and conveying apparatus, a frame, a boom pivotally supported on said frame so as to swing horizontally, a track extending longitudinally through said frame and projecting forwardly beyond the end thereof, said track being carried by the boom, the forward portion of the track being movable relative to the rear portion so that it may be raised and lowered, a trolley adapted to be guided along said track, a digging and conveying bucket supported by said trolley and adapted to be filled with material when moving forwardly along the movable section of the track, ropes connected to the trolley for moving the same back and forth along the track, and means for automatically dumping the bucket at the rear end of the track.

11. In a digging and conveying apparatus, a frame, a boom pivoted to the frame so that it may be swung horizontally, a track carried by the boom, and having its forward portion pivoted so that it may be raised and lowered, a trolley adapted to be guided along said track, a bucket pivotally supported by said trolley, a head rope connected to the trolley for moving the same forwardly and for giving the bucket a digging action when moving along the forward portion of the track, a tail rope for conveying the bucket rearwardly along the track to dumping position, and mechanism for preventing the tilting of the bucket during the digging action.

12. In a digging and conveying apparatus, a frame, a boom pivoted to the frame so that it may be swung horizontally, a track carried by the boom and having its forward portion pivoted so that it may be raised and lowered, a trolley adapted to be guided along said track, a bucket pivotally supported by said trolley, a head rope connected to the trolley for moving the same forwardly and for giving the bucket a digging action when moving along the forward portion of the track, a tail rope for conveying the bucket rearwardly along the track to dumping position, mechanism for preventing the tilting of the bucket during the digging action, and means for automatically dumping the contents of the bucket at the rear end of the track.

13. In a digging and conveying apparatus, a frame, a track supported by said frame, the forward portion of the track being pivoted so that it may be raised and lowered relative to the rear portion, a trolley adapted to be guided along the track, a bucket trunnioned in said trolley, said bucket being open at the front and having at the rear a pivoted door, means for drawing the trolley and bucket forwardly along the track and for giving the bucket a digging action during

the movement along the pivoted portion of the track, a tail rope connected to the trolley for moving the same rearwardly along the track, and a member connected to the 5 track near the rear end thereof for engaging and swinging the door to open position so that the contents may be automatically dumped from the bucket.

14. In a digging and conveying apparatus, a frame, a track extending lengthwise of the frame, the forward portion of the track being pivoted so that it may be raised and lowered, and the track being movable laterally, a trolley adapted to be guided 10 along said track and having a bucket trunnioned thereto, said bucket being open at the front and having at the rear a swinging door, the rear portion of the track being inclined so as to tilt the bucket, a head rope 15 connected to said trolley for moving the 20

same forwardly along the track and for giving the bucket a digging action near the forward end of the track, a tail rope connected to the trolley for moving the trolley and bucket rearwardly, mechanism intermediate 25 of the tail rope and the bucket for holding the bucket against tilting movement when the trolley and bucket are drawn forwardly by the head rope, and for tilting the bucket when a predetermined tension is 30 placed on the tail rope, and means for automatically lifting the door of the bucket when the latter is tilted at said inclined portion of the track.

In testimony whereof, I hereunto affix my 35 signature in the presence of two witnesses.

ROBERT P. GREENLEAF.
